CLOSURE

Georges Monnet, New York, N. Y., assignor to
 Guardian Merchandising Corporation, Montreal, Quebec, Canada, a corporation of Quebec, Canada

Application June 6, 1940, Serial No. 339,058

4 Claims. (Cl. 215—76)

This invention relates to closures and refers more particularly to closures, caps or covers adapted to close the outflow openings of bottles, tubes and other containers.

It is customary to close the opening of a compressible tube containing a pasty substance or of a bottle containing a liquid by means of a cap having an inner helical groove and screwed upon the outer screw threads provided upon the neck of the tube or bottle.

These caps are usually rather small and every day experience shows that they can be easily lost and that it is fairly inconvenient to replace them. In many instances the user neglects to screw the caps sufficiently tightly upon the necks of tubes and bottles carried in bags, pockets or suitcases, with the result that the contents of the containers spill out and cause considerable damage.

An object of the present invention is the provision of a closure which is permanently connected to its container and which can be conveniently and easily manipulated to provide an outflow passage for the contents of the container, and to close this passage.

Another object is to provide a permanent leak-proof closure which can be conveniently manipulated to open and close an outflow passage and which will effectively prevent any escape of paste, liquid or gas while the passage is closed.

A further object is the provision of an airtight and gas tight closure which is so constructed that an increase in pressure within the container carrying the closure will automatically increase the sealing capacity of the closure.

Other objects of the present invention will become apparent in the course of the following specification.

In realizing the objects of the present invention it was found advisable to provide a closure having an inner closure member consisting of an elastic material, such as rubber or cork, and firmly mounted upon the mouth of the container opening. This elastic closure member is prevented from being turned relatively to the container by interengaging ribs and grooves, by glue or by any other suitable means. The elastic closure member is provided with a passage which is eccentrically located relatively to the central axis of the container opening, and which preferably, is limited by surfaces converging in an outwardly direction, namely, in the direction of the inner pressure which may be developed within the container. The elastic closure member and the adjacent part of the mouth of the container, are enclosed by a hard cap which is in engagement with the elastic closure member and is rotatable relatively thereto. The cap is provided with an opening adapted to coincide with the passage of the elastic closure member.

The invention will appear more clearly from

the following detailed description when taken in connection with the accompanying drawing showing, by way of example, preferred embodiments of the inventive idea.

5 In the drawing:

Figure 1 is a top view of a closure constructed in accordance with the principles of the present invention, some parts being shown as broken off.

Figure 2 is a section along the line 2—2 of Figure 1.

Figure 3 is a top view of a somewhat differently constructed closure.

Figure 4 is a section along the line 4—4 of Figure 3.

15 Figure 5 is a top view of a closure of a somewhat different type; and

Figure 6 is a section along the line 6—6 of Figure 5.

Figures 1 and 2 of the drawing show the neck 7 of a container made of glass, although obviously the container may consist of a collapsible tin tube or the like. The neck 7 encloses an outflow passage 8 and is provided with an annular bead 9.

25 The bead 9 has an upper surface or front surface 10 carrying ribs 11 which extend radially upon the bead. The bead projects outwardly beyond the neck 7 thus forming a lower annular surface 12 carrying ribs 13 which are smaller in height and length than the ribs 11.

30 An elastic closure member 14 fits over the container neck 7 and is permanently connected therewith. The closure member 14 may be made of cork, rubber or any other suitable elastic material and it comprises an inner cylindrical portion 15 fitting tightly into the passage 8 of the container 7, and a flange portion 16 situated over the surface 10 of the bead 9.

The closure member 14 has a passage 17 which 40 is eccentrically located in relation to the central axis of the passage 8. The surfaces 18 enclosing the passage 17 are preferably conical in form and converge outwardly in the direction away from the passage 8.

45 The closure member 14 is firmly and permanently connected with the container 7, so that it cannot turn relatively thereto. This may be accomplished by pressing the portion 14 of the closure member 14 firmly into the passage 8 and causing the ribs 11 of the bead 9 to project into and compress the flange portion 16.

If necessary, any suitable additional means may be used to establish a permanent connection between the bead 9 and the closure member 55 14.

The bead 9 and the closure member 14 are covered by a metallic cover or cap 19, the inner surfaces of which are in engagement with the elastic closure member 14. The cover 19 has a skirt portion 20 provided with an inwardly bent

portion 21 which is adapted to slide over the ribs 13 and which may have inner grooves fitting over the ribs 13. The cap may be made of any hard or rigid unelastic material. The skirt 20 of the cover 19 may be hexagonal in form, as shown in Figure 1, to facilitate the turning of the cover.

The cover 19 is provided with an opening 22 which is preferably slightly larger than the adjacent end of the passage 17, and which is adapted to be situated directly over the passage 17 in a certain position of the cover 19.

It is apparent that in the position shown in Figures 1 and 2, no liquid or gas situated within the container 7 will escape through the closure, since the passage 17 is covered by the cap 19. Any inner pressure developed within the container will be exerted upon the converging surfaces 18 of the passage 17 and a component part of this pressure will be directed parallel to the surfaces 18, thereby pressing the elastic closure member 14 more tightly against the metallic cover 19.

Thus an increase in pressure will automatically result in an increased tightness of the closure.

In order to remove the contents of the container, the user turns the cover 19 until its opening 22 is situated over the passage 17. Due to the engagement of the small ribs 13 with the end portion 21 of the skirt 20, the turning of the cover 19 is carried out stepwise, and the danger of an accidental opening of the closure is effectively eliminated.

The device shown in Figures 3 and 4 comprises a container 30 having a bead 31 provided with radial ribs 32. The inner elastic closure member 33 has a large hollow portion 34 enclosed by inner converging surfaces 35. The bead 31 and the closure member 33 are enclosed by a rotary cover 36 provided with an opening 37. As in the construction shown in Figures 1 and 2, the inner elastic closure member 33 is permanently connected with the bead 31, while the outer metallic cover 36 may be conveniently turned to establish a connection between the hollow portion 34 of the closure member 33 and the opening 37, and to interrupt this connection. The curved shape of the surfaces 35 furthers the engagement between the member 33 and the cover 36 should pressure be developed within the container 30.

In the construction shown in Figures 5 and 6 the container 40 is provided with a converging conical neck portion 41, a cylindrical neck portion 42 and a bead 43 having an upper surface 44, a smaller lower surface 45 and a conical converging inner surface 46.

The elastic closure member 47 has an inner conical surface 48 contacting the surface 46 of the container. The conical surfaces 46 and 48 increase the tightness of the closure to a considerable extent, should inner pressure develop within the container.

The ribs 49 carried by the bead 43 press against the closure member 47 and prevent it from turning. A metallic rotary cover 50 is situated over the closure member 47 and the bead 43 and is provided with an opening 51 which may coincide with the conical passage 52 provided in the closure member 47. The skirt 54 of the cover 50 includes a restricted end portion 55 engaging the surface 45 and the neck portion 42.

The upper layer 53 of the closure member 47 may be impregnated with any suitable substance.

which would diminish friction between the closure member 47 and the cap 50, or the layer 53 may consist of foil, paper or the like.

However, the impregnating substance should not interfere with the engagement of the elastic closure member 47 with the rotary cover 50.

It is apparent that the specific illustrations shown above have been given by way of illustration and not by way of limitation, and that the structures above described are subject to wide variation and modification without departing from the scope of the present invention. All of such modifications and variations are to be included within the present invention.

What is claimed is:

1. In a closure, an elastic closure member firmly fitting into a beaded flange-like mouth of a container, and a rotary hard cap covering said elastic closure member and said flange-like mouth and having inner surfaces contacting outer surfaces of said elastic closure member, said elastic closure member having a passage formed therein which is enclosed by outwardly converging surfaces, said cap having an opening formed therein and adapted to communicate with said passage, said flange-like mouth having a surface comprising a plurality of radially extending ribs and grooves formed between said ribs, said cap having a skirt having grooves formed therein and engaging said ribs.

2. In a closure having a closure element and a cap; an outwardly projecting bead enclosing the mouth of a container and including a front surface and a rear surface; a plurality of radial ribs upon said front surface for engagement with said closure element, and a plurality of radial ribs upon said rear surface which are shorter and smaller than the first-mentioned ribs for contacting said cap.

3. The combination of a container having an outwardly projecting bead enclosing the mouth of a container and including a front surface and a rear surface, a plurality of ribs upon said front surface and a plurality of shorter and smaller ribs upon said rear surface; with an elastic closure member firmly fitting into said mouth and comprising a flange portion covering said front surface and engaging the first-mentioned ribs, and a rotary hard cap covering said elastic closure member and having inner surfaces contacting outer surfaces of said elastic closure member, said elastic closure member having a conical passage formed therein, said cap including a polygonal skirt enclosing said bead and having an inwardly bent portion contacting the second-mentioned ribs, said cap having an opening formed therein and adapted to communicate with said passage.

4. The combination of a container having an outwardly projecting bead enclosing the mouth of a container and including a front surface and a rear surface, a plurality of ribs upon said rear surface; with an elastic closure member firmly fitting into said mouth, and a rotary cap covering said elastic closure member and having inner surfaces contacting outer surfaces of said elastic closure member, said elastic closure member having a passage with outwardly converging walls formed therein; said cap including a skirt enclosing said bead and having an inwardly bent portion contacting said ribs, said cap having an opening formed therein and adapted to communicate with said passage in a predetermined position of said cap.

GEORGES MONNET.
